Primary Examiner—Sandra L. Morris[57] **CLAIM**

The ornamental design for a game board, as shown and described.

DESCRIPTION

FIG. 1 is a top plan view of a game board showing my new design, being of conventional thickness, the bottom being plain and unornamented;

FIG. 2 is a top plan view of the gameboard of FIG. 1, embodying four parts divided by figure numbers and zig-zag lines as a whole;

FIG. 3 is a fragmentary top plan view of the upper left corner of FIG. 2;

FIG. 4 is a fragmentary top plan view of the upper right corner of FIG. 2;

FIG. 5 is a fragmentary top plan view of the lower left corner of FIG. 2; and,

FIG. 6 is a fragmentary top plan view of the lower right corner of FIG. 2.
